ABSTRACT

A system is disclosed for synchronizing the recording of visual images and sound. The system includes a tape recorder and a motion picture camera driven in response to signals produced by operation of the tape recorder. These signals result from movement of the tape. The camera feeds a signal back to the tape recorder upon the completion of exposure of each film frame which effects termination of operation of the camera until the next signal is received from the moving tape.

SYNCHRONIZING SYSTEM FOR RECORDING VISUAL IMAGES AND SOUND

This is a continuation, of application Ser. No. 181,313, filed Sept. 17, 1971, now abandon

BACKGROUND

This invention relates to systems for recording visual images and sound and, more particularly, to such a system for synchronizing the recording of sound on tape with the simultaneous recording of pictures taken by a motion picture camera.

There is substantial interest and need for relatively inexpensive equipment for making sound motion pictures. It is desirable to provide a system which enables the use of conventional motion picture cameras for recording visual images and the use of conventional tape recorders for recording sound simultaneously with the recording of the visual images. For desirable results it is essential that the recording of both are synchronized in a manner which ensures a synchronized playback and which permits accurate editing of the sound and visual images.

In order to avoid purchasing expensive special cameras equipped to be used with sound recorders, one traditional approach used by amateur movie makers has been to record the sound on tape during the taking of motion pictures by attempting to synchronize the movement of the tape past the recording head with the movement of the film past a camera lens. This method is inaccurate and unsatisfactory, especially where there are frequent stops and starts during the recording process.

Many attempts have been made to overcome these problems. In one such attempt an independently driven camera and tape recorder are related through circuitry which utilizes a pulsating signal recorded on the sound tape which is intended to correspond to the frames of the motion picture film. This has not proved adequate because the synchronization depends upon the proper governing of the speed of the tape recorder and motion picture camera since each element runs independently and neither is wholly dependent during operation on the other. Another system controls the camera motor speed as a function of the tape speed. This requires a special camera and tape recorder. Furthermore, such equipment requires complex editing equipment to properly edit the film and sound tape, the editing equipment having to compare the recorded pulses with the corresponding frames. Because the comparison depends upon recorded signals the tape and film cannot be visually compared and matched. Also these systems have a tendency to slip which results in loss of lip synchronization (sound compared with lip movement). These and other techniques are considered ineffective and often too expensive to satisfy much of the amateur movie making market, including the home motion picture field.

Copending patent applications Ser. No. 76,437 filed Sept. 29, 1970 entitled Tape and Film Synchronizing Apparatus and Ser. No. 79,829 filed Oct. 12, 1970 entitled Tape and Film Synchronizing System disclose apparatus and a system which overcomes many of the disadvantages of the prior art systems. As disclosed therein the system includes a movie camera and tape recorder each of which is capable of independent operation. When used individually, the camera is actuated by closing a switch which closes a circuit enabling a

battery to energize a motor which in turn drives the film and operates the camera shutter. When the recorder and camera are interconnected the camera trigger switch is disconnected from the camera motor circuit and is connected to the tape recorder so that when the camera switch is closed, instead of the camera motor being energized, the tape recorder motor is energized causing the magnetic recording tape to move past the sound recording head. Means for observing the movement of the tape, such as optical means reading perforations along the edge of the tape, operates an electronic switch which effects completion of the movie camera motor circuit resulting in pulsating actuation of the camera. After each motion picture film frame is exposed the camera circuit is opened and remains open until a subsequent portion of the sound recording tape advances which then recloses the movie camera control circuit and reenergizes the movie camera to expose the next successive frame.

By means of this system the camera is directly controlled by the tape recorder whereby each exposed motion picture frame corresponds to a particular segment of the sound tape. Furthermore, there is no chance that the film will be exposed without the tape recorder operating. Conventional battery operated cameras, with minor and inexpensive modifications, can be used with this system.

Since the camera "turn-on" signal from the tape recorder is generated by an optical system in combination with perforations through the tape, there is provided a means for visually and mechanically linking the sound tape with the movie film, namely the perforations on the sound tape corresponding to the perforations on the movie film. This simplifies editing of the two recordings and avoids slippage during playback, both of which ensures that lip synchronization is maintained.

The system of this invention is an improvement over the system disclosed in the above-referred to copending applications. In addition to improvements in the circuitry employed to obtain the advantages described above, the system of this invention provides greater flexibility of use and eliminates certain potential problem areas as described below by isolating the tape recorder circuit from the camera circuit while preserving the slave relationship of the camera to the tape recorder. This improved system also provides for the length of sound recording tape to equal the length of movie film so that a visual and physical match-up of the two recording mediums can be made to simplify editing the film and tape.

OBJECTIVES

Accordingly, it is one objective of this invention to provide an improved system and apparatus for synchronizing simultaneous recording of visual images and sound on two different mediums, namely, film and tape.

Another objective of this invention is to provide an improved synchronization system and apparatus including one which will permit the use of a wide range of conventional movie cameras having different electrical power requirements without having to modify the synchronizing system and sound recording apparatus.

A still further objective of this invention is to provide an improved synchronization system and apparatus which provides an exposed film and recorded tape capable of easy editing while retaining synchronization.

DESCRIPTION OF THE DRAWINGS

These and other objectives and advantages will be readily apparent from the detailed description below taken together with the drawings in which:

FIG. 1 is a perspective illustration of a motion picture camera and a cassette type tape recorder employing the synchronization system of this invention.

FIG. 2 is an enlarged perspective view of a portion of a tape recorder illustrating the magnetic tape and optical system utilized in the synchronization system of this invention.

FIG. 3 is a block diagram illustrating the improved synchronization system of this invention.

FIG. 4 is a plan view of a portion of a cassette type tape recorder having a magnetic tape brake.

FIG. 5 is an enlarged perspective view of the magnetic tape brake of FIG. 4.

FIG. 6 is a plan view of a portion of a cassette type tape recorder having a second form of a magnetic tape brake.

FIG. 7 is a detailed circuit diagram illustrating one embodiment employing the synchronization system of this invention.

FIG. 8 is a circuit diagram of the brake stop circuit which forms a part of the circuit diagram of FIG. 7.

BRIEF DESCRIPTION

Briefly described, this invention in one form comprises a sound recording device such as a cassette type magnetic tape recorder having an idler wheel and a motor driven capstan for transporting the magnetic tape past a recording head. The tape is perforated along one edge. An optical system for reading movement of the tape and operating an electronic switch for controlling a camera is used. The optical system includes a post containing a light source on one side of the tape and a photocell on the other side of the tape. The perforations permit light rays from the light source to project intermittently onto the photocell which in turn produces a corresponding electrical signal for closing the electronic switch.

The recorder is adapted to be used in combination with an electrically operated visual image recorder such as a battery operated motion picture camera. The camera is of conventional design and includes an on-off switch for making and breaking a circuit energizing the camera motor which causes the film to move past a lens. The camera often includes an electrical switch which is closed periodically to correspond to the opening of the camera shutter in order to provide an electrical signal for operating a photoflash unit in conjunction with the opening of the shutter.

In order for a conventional camera to be used with the synchronization system of this invention, the camera is modified by adding a terminal adapted to receive a contact dissociating the camera motor from direct connection with the camera motor power source and providing circuit linkage between the camera motor power source and the tape recorder. Closing of the electronic switch as a result of the signal provided by the photocell energizes the camera motor. A second terminal which is conventionally on many cameras but, if not, which can be added provides an electrical connection to receive the photoflash operation pulses and to utilize those pulses to open the electronic switch after it has been closed by the pulse from the photocell. Opening the electronic switch stops operation of the

camera motor. The camera motor is then controlled by the electronic switch and, consequently, is the slave of the tape recorder.

In order to simultaneously record visual images and sound, the operator closes the camera switch causing the tape recorder to operate. With the tape recorder operating, the magnetic tape passes between the light source and photocell producing an electrical pulse which closes an electronic switch thereby energizing the camera motor and causing the film to move past the lens. As each frame of the film is exposed an electrical synchronization pulse is received from the photoflash circuit which is directed to the tape recorder circuit to open the electronic switch turning the camera motor off until such time as the next perforation through the magnetic tape passes the photocell producing a pulse and reclosing the electronic switch to again actuate the camera motor. In this manner each frame of the film corresponds to a precise portion of the magnetic tape defined by the perforations. Because the camera is slaved to the tape recorder, the camera will not operate if there is a defect in the recorder, such as if the recorder is not operating, if the magnetic tape is improperly placed within the recorder, if the light source is not operating, or if the tape is used up.

For purposes of simplifying editing of the film and tape without losing lip synchronization the perforations through the tape are spaced equally with, or some multiple of, the perforations through the movie film. Also, since normal tape recorder speed is not equal to standard movie film speed, the tape recorder of this invention is provided with a speed selector enabling use of conventional tape recorder speed wherein the recorder is not being used in conjunction with a camera and a tape speed equal to film speed when the recorder is used with a camera. In this manner, one inch of movie film corresponds to one inch of magnetic tape.

In order to abruptly terminate movement of the sound recording tape upon opening of the camera switch when it is desired to cease recording the visual images and sound, a brake is provided which physically grabs a pulley belt or flywheel which is used to drive the tape drive capstan. One form of brake mechanism comprises an electromagnet which attracts a leaf spring normally biased toward a position away from the belt, the belt passing between the leaf spring and a belt guide member. When the electromagnet is energized the leaf spring is forced to bear against the belt and belt guide member instantly stopping movement of the belt and, therefore, the drive capstan and magnetic tape. The electromagnet is actuated through a stop circuit which includes a normally off-biased transistor, a resistive member, and a charge storage member such as a capacitor. While the tape recorder is on, the transistor is biased off. As soon as the recorder circuit is opened, current flows through the resistive member charging the capacitor. During the initial period of capacitor charging, the voltage drop across the resistive member biases the transistor on and the transistor remains on until the voltage drop falls below the required level. While the transistor is on or closed, the tape recorder battery energizes the electromagnet which actuates the brake until the transistor turns off. This period of time is sufficient to terminate movement of the magnetic tape. If the recorder is turned on immediately after it is turned off, the resistive member and capacitor are shorted biasing the magnet control transistor off thereby inactivating the magnet and the leaf spring releases the belt

permitting the tape recorder to operate.

Detailed Description

Camera and Tape Recorder

With reference to the drawings, and particularly FIG. 1, there is illustrated apparatus for recording simultaneously visual images and sound. Conventional electrically powered motion picture cameras 10 can be easily and inexpensively modified to permit them to be used with the system of this invention. The modification includes the addition of one or two small terminals 12 adapted to receive recorder cables 14 for purposes which are described below.

The battery operated camera 10 normally includes an on-off switch in the form of a trigger 16 such that when the trigger is depressed a switch is closed directly connecting a battery to the camera motor which in turn advances the film past a shutter in pulsating movements so that as each successive frame is presented to the shutter its motion is stopped while the shutter is opened exposing the film frame to the subject being photographed. After the shutter is closed the next frame is advanced into place. The camera operating mechanism is commercially available and does not form a part of this invention.

In order to record sound simultaneously with the recording of the visual images there is provided a magnetic tape recorder 20. For illustrative purposes, a cassette type recorder is illustrated and will be discussed throughout this specification. The magnetic tape is stored within a cassette 22 which is a sealed plastic housing containing two reels with a magnetic tape permanently attached at its ends to the reels. The cassette may be instantly and easily loaded into or removed from the tape recorder 20. The recorder is electrically connected to the camera 10 by two cables 14 which can be easily disconnected to allow the camera and recorder to be used individually. The recorder is light and adapted to be carried by means of a shoulder strap 24. The magnetic tape recorder 20 may be a standard battery operated recorder modified to include the synchronization system of this invention.

As is described in copending patent application S.N. 76,437 referred to above and the specification of which is incorporated herein, the synchronization system employs a magnetic tape having perforations along one edge thereof, the perforations in combination with an optical and electrical system serving to generate pulses to actuate the camera 10. While perforations are preferred other spaced indicia capable of being sensed electrically, magnetically, optically or tactilly can be used. With reference to FIG. 2, there is illustrated two posts 26, 27 mounted on one side of a perforated magnetic tape 30. These posts normally are found in a conventional tape recorder located adjacent to a recording head 32 to serve as guide posts for placing the cassette 22 in its proper position, the posts being received by apertures 23, 25 in the cassette. For the synchronization system of this invention, one of the posts 26 are hollowed out and is supplied with a miniature light bulb 28, one type being commercially identified as Tungsol TS-30. An aperture 34 extends transversely through the post 26 aligned with the perforations 36 through the tape 30.

A photocell 38 in the form of an integrated circuit which includes a pulse shaper and amplifier is mounted in alignment with the aperture 34 of the post 26 on the

opposite side of the tape 30. This type of photocell is available commercially, such as the Centralab photocell C.R.L. No. OH102. By being aligned with the post aperture 34 the photocell 38 receives the light rays from the bulb 28 which pass through the tape perforations 36. The photocell 38 provides an electrical pulse each time a perforation 36 passes in alignment with the aperture 34 and photocell 38 and, consequently, the pulses from the photocell correspond with the movement of the magnetic tape 30.

Camera and Tape Recorder Circuits

Turning now to FIG. 3, a schematic diagram of the camera circuit 40 is shown. The camera 10 includes a battery 41, a motor 42 and a two position on-off switch 44 operated by the camera trigger 16. The circuit comprising the battery 41, motor 42 and switch 44 exists in standard electrically powered cameras. To adapt the standard camera so that it may be used with the synchronization system of this invention a terminal 12 is added which includes an annular contact 46, a spring loaded movable contact 48 and a stationary contact 50. When the contact 48 is in its normal position it is in electrical connection with the stationary contact 50 which in turn is connected to the switch 44. The contact 48 also is in electrical connection with the camera motor 42 so that closing the switch 44 completes a circuit through the motor 42 and battery 41. When the contact 48 is moved away from contact 50 by insertion of a plug contact 52 in the terminal 12, there is a break in the camera motor circuit 40 and closing the switch 44 will not energize the camera motor.

Many electrically operated cameras are provided with means for synchronizing a photoflash unit (not shown) with the camera shutter so that if desired each time the shutter opens an electrical signal is provided to the photoflash unit to generate a flash of light. Such a system is schematically illustrated in FIG. 3 as including a switch 55 comprised of a pair of normally spaced contacts 56, 58, a flash control cam 60 and a terminal 62 connected in series with the battery 41. The cam 60 is driven by the camera motor 42 and is designed so that the high point 64 of the cam closes the switch 55 at the end of a frame exposure and just prior to the next successive opening of the camera shutter. The cam 60 also serves to keep the camera motor operating so as not to terminate operating in the middle of a frame. The associated means for doing this is standard and not shown. The terminal 62 is adapted to receive a plug contact (not shown) from the photoflash unit so that each time the contacts 56, 58 are closed by the cam 60 an electrical signal is transmitted to the flash unit to actuate the flash in synchronization with the opening of the shutter. A camera which is not equipped with this system can be modified to include it easily and inexpensively.

The tape recorder 20 conventionally includes a motor 70 in series with a battery 72. The motor drives the magnetic tape 30 through conventional tape transport means including a pulley belt 74 and pulley 75 driving a flywheel 76 which in turn drives a capstan 78 at constant speed, the capstan being mounted on the flywheel shaft. The tape 30 which is located between the capstan and an idler wheel 79 is moved by the rotating capstan. The flywheel also effects rotation of take-up reel post 80 over which a cassette take-up reel 81 is placed, the take-up reel receiving the tape 30 from a supply reel 82 mounted over a post 83. The tape, in

passing from the supply reel 82 to the take-up reel 81, passes by the cassette guide post 26, 27 and photocell 28.

The synchronization system of this invention requires the addition of the following circuitry to conventional tape recorder circuitry. A two position switch in the form of a standard reed relay 84 is placed in series with the motor 70 and battery 72. A recorder cable 14 has one end connected to the tape recorder 20 and the other end is provided with a plug contact 52 adapted to mate with the camera terminal 12. The plug contact 52 includes a conductive outer sleeve 88 adapted to electrically engage the annular contact 46 and a central post 90 adapted to electrically engage the movable contact 48. When the plug contact 52 is inserted in the terminal 12, the central post 90 causes the contact 48 to move away from the stationary contact 50 thereby breaking the circuit 40 involving the camera motor 42, battery 41 and camera on-off switch 44. In place of that circuit the battery 41 and camera switch 44 are placed in circuitry with the tape recorder 20 by means of the contact 52 and the relay 84. Depressing the camera trigger 16 closes the switch 44 putting the camera battery 41 in series with the reed relay 84 to effect closure of the relay. When the relay 84 is closed the tape recorder battery 72 energizes the tape recorder motor 70 which then drives the tape transport system. The battery 72 also energizes the light 28 in the post 26.

In order to permit the tape recorder 20 to be used as a conventional recorder independent from the camera 10 switch means 91 is provided which, when closed manually, places the battery 72 in circuit with the tape recorder motor 70 bypassing the camera controlled relay 84.

As the magnetic tape 30 moves by the lighted post 26 the photocell 38 receives light pulses through the perforations 36 in direct relation to the speed at which the magnetic tape 30 is moving and produces an electrical pulse or signal for each light pulse it receives. Each signal is amplified and squared by the amplifier which is part of the photocell integrated circuit. The signal then turns on a bistable trigger circuit 94, such as a Schmitt trigger, which provides a signal of predetermined amplitude independent of the magnitude of the light pulse. The trigger signal is amplified by an amplifier circuit 95 and is utilized to close a camera control reed relay 96. Closure of the relay 96 completes the camera circuit through the center post contact 90 of the plug contact 52 and movable contact 48 resulting in actuation of the camera motor 42.

A second recorder cable 14 having a plug contact 100 on one end is inserted within the photoflash terminal 62 in order to conduct the electrical pulse intended for the photoflash unit as described above to a pulse circuit 92 in order to turn off the bistable trigger circuit 94 after each motion picture film frame is exposed. With the bistable trigger in the "off" mode, the camera control relay 96 opens turning the camera off. In this fashion the photoflash pulse becomes a synchronization pulse. The pulse circuit ensures that the turn-off pulse is of the proper polarity to accomplish its purpose. As can be seen, the magnetic tape 30 passing between the post 26 and photocell 38 effects generation of an electrical pulse for each perforation 36 through the tape 30. The electrical pulse generated by virtue of movement of the magnetic tape 30 actuates the motion picture camera which causes the film to advance one frame at which time the camera motor circuit is opened

by the relay 96 due to the fact that the trigger circuit has been turned off by the synchronization pulse. The camera motor circuit is closed again when the next successive magnetic tape perforation 36 passes between the post 26 and the photocell 38. In other words, the magnetic tape perforations in effect turn the camera on and the synchronization pulse turns the camera off at the end of each frame. It can be appreciated that each frame of the motion picture film corresponds to the portion of the magnetic tape between adjacent perforations. The perforations on the film and tape permit direct mechanical and visual synchronization of the sound recording tape and visual image recording film.

If the tape recorder speed varies even slightly as a result of load, atmospheric conditions, battery conditions, etc., synchronization will remain because the camera is slave controlled by movement of the magnetic tape 30. Furthermore, the camera 10 will not operate and film will not be exposed if the tape recorder 20 is not operating properly. For example, if the light bulb 28 is not on or if the cassette 22 is placed upside down in the recorder 20 so that the perforations are not aligned with the photocell 38 no light will be transmitted to the photocell to generate a camera "turn-on" signal. Similarly, when the magnetic tape 30 is used up no additional light pulse will be received by the photocell 38 and, consequently, the camera will not continue to operate. Because the photocell is very sensitive and because the signal from the photocell 38 is squared and amplified to the desired level, a proper signal will be received by the trigger circuit 94 even though the light source 28 providing the light signal varies in intensity. Consequently lip synchronization will be maintained over the usable life of the tape recorder battery. By using the relays 84, 96 in the tape recorder 20 and by having the turn-on signal powered by the tape recorder battery 72 and not dependent upon the camera battery 46 the tape recorder power circuit is electrically isolated from the movie camera power circuit. This adds flexibility of use to the synchronization circuit because the tape recorder 20 can be used with various cameras having wide power requirements without having to control or modify the current available in the camera motor circuit to make it compatible with the tape recorder circuit. This is one improvement of the system of this invention over the synchronization system of the above referred-to copending application Ser. No. 76,437.

Magnetic Tape Brake (FIGS. 3 - 6)

In order to maintain lip synchronization, it is necessary to effectively stop movement of the perforated magnetic tape 30 immediately upon release of the camera trigger 16. When conventional tape recorders are turned off the tape continues to advance a short distance due to the inertia of the flywheel 76 which drives the capstan 78. This movement cannot be tolerated if synchronization is to be maintained. FIGS. 3, 4 and 5 illustrate one form of mechanical brake 108 which effectively instantaneously stops movement of the capstan 78 and thereby terminates movement of the tape 30 upon release of the camera trigger 16.

A stop circuit 110 is included within the tape recorder 20 and is mounted in parallel with the relay 84 and in series with the tape recorder battery 72 and motor 70. The stop circuit 110, which is illustrated in detail in FIG. 7 and described below includes a capacitive-resistive circuit which controls the operation of the

brake 108. When the camera trigger 16 is released opening the camera motor switch 44 and deenergizing the relay 84, the stop circuit 110 energizes an electromagnet 112 which operates the brake 108 and stops further movement of the magnetic tape 30.

FIGS. 4 and 5 show the brake in detail. The belt 74 which drives the flywheel 76 passes over a pulley guide support 116 which is mounted between the brake control electromagnet 112 and a magnet leaf spring brake arm 118. When the electromagnet 112 is energized by the stop circuit 110 the brake arm 118 is instantly drawn toward the magnet 112 and mechanically grabs the belt 74 preventing further movement of the pulley 75 and, consequently, of the flywheel 76, capstan 78 and magnetic tape 30. Upon completion of the operation of the stop circuit 110 the magnet 112 becomes deenergized and the resiliency of the leaf spring brake arm 118 causes the arm to move away from the magnet 112 freeing the belt 74. By virtue of this inexpensive, positive brake mechanism the magnetic tape 30 is stopped in its movement virtually simultaneously with release of the movie camera switch trigger 16 preserving the synchronization between the magnetic tape 30 and the movie film. Furthermore, the brake mechanism makes minimal demands upon the tape recorder battery 72 and draws no power during operation of the recorder. Since it draws no power during operation of the tape recorder, the brake does not constitute a drain on the battery.

FIG. 6 illustrates a second form of mechanical brake which is a preferred brake mechanism 119. The brake mechanism 119 comprises a solenoid 120, a brake shoe 121 and a return spring 122. The brake shoe 121, which is of molded plastic and lined on the inner surface with a conventional brake material 123, such as rubber impregnated canvas, is contoured to the shape of a substantial portion of the periphery of the flywheel 76 and is pivotally mounted at one end to the tape recorder housing by a pivot pin 124. The other end of the brake shoe is provided with an iron rod or plunger 125 which is located partially within the solenoid 120 and the solenoid is connected to the same stop circuit 110 which was partially described above and which is described in greater detail below in connection with FIG. 7. The return spring 122 opposes the force of the solenoid and returns the brake shoe to its normal position spaced slightly from the flywheel 76, in the order of 0.0625 inches. The return position is established by an adjustable stop 126. The return spring 122 is located near the pivot pin 124 and away from the solenoid 120 to provide the solenoid with a greater moment arm in countering the spring force and, therefore, helps minimize the force required of solenoid.

When the camera trigger 16 is released opening the camera motor switch 44 and relay 84 the stop circuit 110 immediately energizes the solenoid 120 which draws the brake shoes 121 against the flywheel 76 stopping rotation of the capstan 78.

The stop circuit allows the solenoid to draw current only when the tape recorder is turned off and even then only long enough to stop movement of the capstan. Therefore, the solenoid places a minimal burden on the tape recorder battery 72.

Detailed Circuit Diagram of Preferred Embodiment

FIG. 7 is the circuit diagram illustrating in detail the circuits shown in block schematic form in FIG. 3 and described above. Corresponding circuits outlined by

dashed lines are identified by the same indicia used in FIG. 3. As can be seen, the circuit of the tape recorder 20 includes a relay 84 which is controlled by the camera switch 44 and battery 41. When the relay 84 is closed the tape recorder motor 70 is energized with current from the battery 72.

The light 27 in post 26 passing through a perforation 36 in magnetic tape 30 illuminated the photocell integrated circuit 38 to provide a "turn on" pulse which pulse is shaped (squared) and amplified by the photocell integrated circuit 38. In this circuit 38 the pulse is amplified to a level which insures activation of the bistable switch formed by the Schmitt trigger circuit 94. When the Schmitt trigger is activated its signal, which is of a predetermined amplitude not necessarily proportional to that of the turn-on pulse from the photocell, is further amplified by the relay amplifier 95 in order to provide a current sufficiently large to close the camera motor relay 96 and energize the camera motor 42 with current from the battery 41. While a Schmitt trigger 94 is employed in the embodiment illustrated, other quick acting bistable triggers of conventional design could be utilized.

After the camera motor advances and exposes one complete frame of the motion picture film the synchronization pulse from the switch 55 is fed to the pulse circuit 92 which ensures that a "turn-off" pulse of proper polarity is directed to the bistable trigger circuit 94 in order to open the camera motor relay 96 and stop the camera motor 42. The relay 96 remains open until the next tape perforation 36 permits light to illuminate the photocell providing a "turn-on" pulse.

FIGS. 7 and 8 illustrate in detail the stop circuit 110 for activating the brake electromagnet 112 or solenoid 120. The stop circuit 110 includes an electronic valve such as a transistor 127 of the type known as a Darlington transistor, a silicon rectifier 128, a resistor 129 and a capacitor 130.

The resistor 129 and capacitor 130 are connected in series with the battery 72 and the side of the capacitor which is connected to the negative side of the battery also is connected to control element, or base, of the transistor 127. The rectifier 128 is across the resistor 129.

When the recorder 20 is used in conjunction with the camera 10 and the camera switch 44 is closed the relay 84 is closed and the tape recorder motor 70 is energized. During operation of the tape recorder the normally closed relay 84 shorts out the resistor 129 and capacitor 130 and biases the transistor 127 off rendering the transistor normally open. Consequently, while the tape recorder is operating the transistor 127 and electromagnet 112 (or solenoid 120) draw no current. The instant the camera switch 44 and relay 84 open, the capacitor 130 charges through the resistor 129.

During the initial charging period the voltage at the juncture of the resistor 129 and capacitor 130 is sufficient (at least 0.7 - 1.0 volts) to turn on the transistor 127 and energize the electromagnet 112 (or solenoid 120). The transistor remains on until the charge on the capacitor 130 rises to the level where the current through the resistor 129 is too low to provide the necessary voltage to maintain the transistor on. At that time the transistor "opens" and the capacitor 130 retains its charge preventing the transistor from closing because when the capacitor is charged no current flows through the resistor 129 and there is no voltage drop across the resistor. Therefore, there is no voltage applied to

60 the capacitor 130. The transistor 127 remains off until the voltage at the juncture of the resistor 129 and capacitor 130 drops to a level where the current through the resistor 129 is sufficient to turn on the transistor 127. At that time the capacitor 130 is discharged through the resistor 129 and the voltage at the juncture of the resistor 129 and capacitor 130 drops to a level where the current through the resistor 129 is too low to provide the necessary voltage to maintain the transistor on. At that time the transistor "opens" and the capacitor 130 retains its charge preventing the transistor from closing because when the capacitor is charged no current flows through the resistor 129 and there is no voltage drop across the resistor. Therefore, there is no voltage applied to

the transistor base. It can be seen that the resistive-capacitive circuit 129, 130 turns on the transistor 127 for a predetermined period of time set by the r-c (129-130) time constant and then turns the transistor off. The time that the transistor is on is sufficient to terminate rotation of the flywheel 76 and capstan 78.

In order to reset the stop circuit 110 for subsequent activation of the brake it is necessary to discharge the capacitor 130. This is accomplished when the relay 84 is closed to turn on the tape recorder. To reduce the capacitor discharge time a rectifier 128 is used so that the capacitor discharges essentially instantaneously through the rectifier upon closing the relay 84.

A second capacitor 131 is placed across the electromagnet 112 (or solenoid 120) in order to increase the rate of current through the coils and the braking action when the transistor 127 turns on. Because of the high inductive reactance of the electromagnet (or solenoid) its actuation tends to be relatively slow; however, the capacitor 131 reduces the circuit's reactive impedance to substantially increase its speed of activation. The capacitor 131 increases the response of the magnet and also delays the complete termination of energy supplied to the electromagnet when the transistor is turned off.

In addition to the features and circuitry illustrated and described above with reference to FIG. 3, the circuit illustrated in FIG. 7 also includes other features which increase the flexibility of use of the tape recorder 20. The recorder 20 includes a three position speed selector switch 140 connected to an electronic conventional motor speed control 142 enabling manual selection of the conventional tape recorder speed of 1 $\frac{1}{2}$ inches per second (ips) for normal (non-movie synchronization) use, four film synchronization use at 3 inches per second when simultaneously recording sound in connection with the taking of movies at the rate of 18 frames per second or 4 inches per second when the camera speed is 24 frames per second. The speeds of 3 ips and 4 ips are selected in order that the distance between each pair of perforations in the magnetic tape corresponds to a frame of the motion picture film and also so that each inch of magnetic tape 30 corresponds to an inch of movie film. If desired the motor speed control 142 can operate the tape recorder motor 70 at other speeds if the camera is designed to operate at different speeds. The speed selector switch 140 and its associated circuitry is designed so that when the tape recorder is used in the non-synchronization mode, i.e., at a speed of 1 $\frac{1}{2}$ ips, the light 27 in post 26 is not energized thereby precluding operation of the camera together with the tape recorder at an improper speed. The light is energized only at the speeds intended for use in combination with the camera thereby conserving the battery 72 and light bulb 27 when the recorder 20 is used as a conventional recorder and not in combination with the camera. The non-synchronization mode on the selector switch 140 also serves the purpose of the switch means 91 illustrated in FIG. 3.

By establishing an inch-for-inch correspondence between the magnetic tape 30 and movie film editing of the magnetic tape and movie film without losing lip synchronization is simplified. Once corresponding points on the tape and film are established and marked the two recording mediums can be mechanically aligned. This also simplifies accurately transcribing the recorded sound on the film stripe (edge) if such is desired. The perforations through the tape when used

with a sprocket on a playback tape deck prevent slippage and a concomitant loss of synchronization.

What is claimed is:

1. Apparatus for synchronizing the recording of visual images and sound comprising:
  - an electrically powered motion picture camera having a camera motor, a first source of electrical energy and a manually actuatable first control switch, a tape recorder including means for holding a recording tape, a tape recorder motor adapted to move whatever tape is held therein, a second source of electrical energy, and a second control switch, said second control switch being responsive to the actuation of said manually actuatable first control switch of said camera to turn on said tape recorder motor and cause movement of said tape,
  - a sensing unit responsive to the movement of tape moved by said tape recorder motor to generate a turn-on electrical signal in response to each passage of a predetermined length of tape,
  - bistable switching means having a first state and a second state, said bistable switching means being responsive to said turn-on signal to be switched into said first state in response thereto,
  - a third control switch having an on-state and an off-state, said third control switch turning on said camera motor when in said on-state, said third control switch being responsive to the state of said bistable switching means to be turned on in response to said first state of the bistable switching means and to be turned off in response to said second state of said bistable switching means,
  - an automatic control switch in said camera to generate a turn-off electrical signal in response to each passage of a predetermined length of film, said bistable switching means being responsive to said camera turn-off signal to be switched into its second state in response thereto, thereby switching said third control switch into its off-state and turning off said motor of said camera.
2. The system of claim 1 wherein said second control switch is a relay, said relay being actuated when said first control switch is actuated, said relay controlling the coupling of said second source of electrical energy to said tape recorder motor.
3. The system of claim 2 wherein said third control switch is a second relay, said second relay being responsive to said bistable switching means.
4. The system of claim 1 wherein said predetermined length of tape is equal in length to said predetermined length of film.
5. The system of claim 2 wherein said predetermined length of tape is equal in length to said predetermined length of film.
6. The system of claim 3 wherein said predetermined length of tape is equal in length to said predetermined length of film.
7. The system of claim 1 wherein said first state of said bistable switching means is an on state and said second state of said bistable switching means is an off state.
8. The system of claim 2 wherein said first state of said bistable switching means is an on state and said second state of said bistable switching means is an off state.
9. The system of claim 4 wherein said first state of said bistable switching means is an on state and said second state of said bistable switching means is an off state.

state.

10. The system of claim 6 wherein said first state of said bistable switching means is an on state and said second state of said bistable switching means is an off state.

11. The synchronizing system of claim 1 wherein said sensing unit includes an optical sensor and wherein said optical sensor generates said turn-on electrical signal

responsive to optical indicia on tape moved by said tape recorder motor.

12. The synchronizing system of claim 1 wherein, said sensing unit further includes an optical sensor and lamp means, said sensor being responsive to light from said lamp means passing through perforations in tape moved by said recorder motor.
